UNITED STATES PATENT OFFICE.

ANDREW A. KRAMER, OF KANSAS CITY, KANSAS.

POULTRY-HOUSE.

1,104,197.

Specification of Letters Patent.

Patented July 21, 1914.

Application filed October 4, 1910. Serial No. 585,270.

To all whom it may concern:

Be it known that I, ANDREW A. KRAMER, a citizen of the United States, residing at Kansas City, in the county of Wyandotte and State of Kansas, have invented certain new and useful Improvements in Poultry-Houses; and I do declare the following to be a full, clear, and exact description of the invention, such as will enable others skilled 5 in the art to which it appertains to make and use the same, reference being had to the accompanying drawings, and to the letters and figures of reference marked thereon, which form a part of this specification.

10 My invention relates to poultry houses and has for its object to provide a structure which is thoroughly sanitary and fire proof. In accomplishing this object I provide a sheet metal structure having suitable doors and 15 ventilating openings, an inclined platform, and roosts located above the platform, as shown in the accompanying drawings and hereafter more specifically described and claimed.

20 In the drawings: Figure I is a view of a poultry house constructed according to my invention, parts of the shell being broken away to show the interior construction. Fig. II is a central vertical section of the house. Fig. III is a horizontal section on the line 25 III—III, Fig. I. Fig. IV is an enlarged sectional view of a portion of the house and roof, illustrating the adjustable mounting of the roof. Fig. V is a view of a modified 30 form of same. Fig. VI is a detail view of one of the ventilating windows. Fig. VII is an enlarged horizontal section of the main door and its mounting. Fig. VIII is a detail view of the locking mechanism on the 35 40 ventilating window. Fig. IX is an enlarged detail view of the mounting for the upper end of the roost beams. Fig. X is an enlarged perspective view of the poultry door.

Referring more in detail to the parts: 1 45 designates a sheet metal shell which may be constructed in a single piece, the ends of which are provided with angle irons 2, so that when the shell is shaped and the ends brought together, the angle irons may be 50 riveted or bolted to each other to form an inclosure.

3 designates a base which is preferably in the form of an angle bar, the upper flange of which is adapted for projection into the 55 interior of the shell, so that the latter may seat on a horizontal portion of the base and

be held in position and retained in shape by the inner flange 4.

5 designates a roof section which is adapted to rest on the upper end of the shell and has a vertical flange 6 projected into the upper end of shell 1 and provided with apertures 7 which may register with apertures 8 in the upper end of said shell to provide suitable ventilation.

65 While the flange 6 preferably fits snugly within the shell, it is adjustable relative thereto, so that when desired the roof may be lifted, so that air may be admitted independently through the flange apertures 7 and shell apertures 8, to afford additional ventilation. I prefer to have the inclined portion of the roof extended beyond the vertical sides of the shell to provide eaves and also to provide the roof with a ventilating 70 cap 9 of ordinary construction.

75 Within the shell 1 is a main entrance opening 10, at the side edges of which are riveted the angle iron jambs 11, the material of the shell being preferably turned 80 back over the inner flanges of the angle pieces, as illustrated in Fig. VII.

85 Hinged to the shell at one side of the opening 10, is a door 12, the hinges 13 of which are so constructed that the door may seat into the recess formed by the facing angle pieces 11 to afford protection from wind, rain etc. At the side of the opening, opposite that to which the hinges are attached, is a staple 14, and secured to the door 90 is a hasp 15 which is adapted for connection with said staple in the ordinary manner.

95 In the upper part of the shell is a ventilating opening 16 which is preferably covered with a wire mesh, channel irons 18 being secured to the inner face of the shell along the edges of the opening to stiffen said edges.

100 Within the shell and extending from near the bottom thereof is an inclined droppings platform 20, the sides of which are rounded to fit against the sides of the shell 1, and the upper edge of which is cut straight as shown in Figs. I and II. This platform is preferably supported by brackets 21 which may 105 be riveted to the sides of the shell. Near the upper end of the shell are hangers 22 for supporting the upper ends of the roost beams 23, the lower ends of which are provided with notches 24 that fit over the 110 straight edge of the droppings platform 20. The beams 23 are provided at regular in-

tervals throughout their length with grooves 25, within which the roost bars 26 are mounted.

Within the shell 1, at the base of the platform 20, is a clean-out opening 27 and secured to the outer face of the shell adjacent the opening are channel irons 28 between which a door 29 is adapted to slide vertically. Extending between the upper and lower ends of the channel members are stops 30, having horizontal members 31 provided with apertures 32, and on the door 29 are the upper and lower horizontal flanges 33 having apertures 34 adapted to register with the apertures in the stop members, so that the shank of a padlock may be projected therethrough when it is desired to secure the door in either an open or closed position. The shell 1 is also provided, at a point below the droppings platform 20, with an opening 35, through which the poultry may enter or leave the interior of the shell; this opening being also provided with a sliding door similar to the construction of the clean-out door, just described.

36 designates nests which may be located on the floor of the poultry house.

A house of this kind may be shipped flat and erected at its destination by riveting or bolting the angle members of the shell together; setting the roof on the top of the shell; riveting the platform within the shell, and mounting the roost beams on the straight edge of the droppings platform 35 and within the hangers 22.

If sufficient ventilation is furnished by the opening 16 and cap 9, the roof may be turned to close the openings 6-8 in the roof flange and shell respectively. If more ventilation is required, these openings may be brought into registration, so that air may pass therethrough, and if still further ventilation is desired the roof may be raised so that air may pass independently through the apertures in the roof flange and shell.

When it is desired to clean the poultry house, it is only necessary to open the door 29 and remove the droppings therethrough; the cleaning operation being facilitated by the droppings inclination of the platform 20.

It is apparent that when the main door of the house is closed the poultry may enter and leave through the opening 35, so that they may have access to the roost through the space between the straight edge of the

inclined droppings platform and the main door, as illustrated in Fig. II. It is also apparent that by extending the roost over the inclined droppings platform, droppings 60 will collect at the lower edge of the platform near the clean-out opening and the cleaning operation be facilitated.

The ventilating features of the improvement have been described and are clearly 65 apparent from the drawings.

Having thus described my invention, what I claim as new therein and desire to secure by Letters-Patent is:—

1. A poultry house comprising an inclosure, a droppings board located in an inclined position within the inclosure with its sides and lower edges contacting sides of the inclosure and its upper edge spaced from the inclosure to provide an opening to the upper portion thereof, and a roost inclined 70 over the droppings board with its lower end supported on the upper end of said board.

2. In a poultry house, an inclosure having an entrance at one side and a clean out opening at the opposite side, a droppings board arranged in an inclined position within the inclosure with its sides and lower end adjacent the sides and rear of the inclosure, its rear edge located below the clean out 80 opening and its upper edge spaced from the entrance to provide access to the upper portion of the inclosure, and a roost having its lower end supported on the upper end 85 of the droppings board and inclined backwardly away from the entrance, substantially 90 as set forth.

3. In a poultry house, an inclosure, circular in cross section and having an entrance at one side and a clean out opening 95 at the opposite side, a droppings board arranged in an inclined position with its sides and lower edge adjacent the inner surfaces of the inclosure and its upper edge spaced therefrom to provide access to the upper portion of the inclosure at the front thereof, and a roost having its upper end supported 100 by the inclosure and its lower end supported by the upper end of the droppings board, substantially as set forth.

In testimony whereof I affix my signature in presence of two witnesses.

ANDREW A. KRAMER.
